UNITED STATES PATENT OFFICE.

BERT G. DUNHAM, OF HAWTHORNE, NEW JERSEY, ASSIGNOR, BY MESNE ASSIGNMENTS, TO WESTERN ELECTRIC COMPANY, INCORPORATED, A CORPORATION OF NEW YORK.

AUTOMATIC TELEPHONE-EXCHANGE SYSTEM.

1,196,532.

Specification of Letters Patent. Patented Aug. 29, 1916.

Application filed June 7, 1915. Serial No. 32,689.

To all whom it may concern:

Be it known that I, BERT G. DUNHAM, a citizen of the United States, residing at Hawthorne, in the county of Passaic and 5 State of New Jersey, have invented certain new and useful Improvements in Automatic Telephone-Exchange Systems, of which the following is a full, clear, concise, and exact description.

10 This invention relates to telephone exchange systems employing machine switching, and more particularly to what are known as two-wire systems. In such systems it is customary to employ two slow 15 acting relays for controlling a selector, one energized by impulses from the front contact of the stepping relay to maintain the release circuit open, and the other by impulses from the back contact of the stepping relay 20 and thus, at the termination of the line circuit interruptions caused by the sender transmitting the digit of the called number involved in the operation of the selector in question, becoming deenergized to bring 25 about the necessary circuit changes to close the secondary stepping magnet circuit to initiate the trunk hunting operation.

It is the object of this invention to provide an efficient selector circuit of this character wherein a single relay performs the functions which hitherto required the two slow relays above mentioned.

In accordance with this invention, a slow relay is employed adapted to be initially 35 energized over the front contact of the stepping relay to open the release circuit. Upon the first primary step of the selector switch shaft, an off-normal spring transfers the control of said slow relay to the back 40 contact of the stepping relay. Thus while the slow relay energizes upon the extension of the calling line to the first selector due to the energization of the stepping relay, and thus opens the release circuit, it is de- 45 pendent for its maintained energization upon impulses received over said armature and back contact, and consequently allows its armatures to retract when the sender in reaching its normal position, after inter- 50 mittently opening the line circuit, maintains the stepping relay energized. The armature of said slow relay in retracting brings about the necessary circuit changes to initiate the hunting operation, the release cir- 55 cuit during this period being maintained

open due to the energization of the stepping relay in a circuit controlled at the calling party's switchhook.

The invention will be more readily understood when described with reference to the 60 accompanying drawing which shows only so much of a telephone exchange system as is necessary for an understanding of the invention.

The calling line whose substation is design- 65 nated A may be associated in any well-known manner with the selector shown, as, for example, by a line finder whose brushes 10, 11 and coöperating stationary terminals 12, 13 only are shown. When the calling 70 line has been thus extended to the selector which may be the first in the chain involved in extending the calling line, the stepping relay 14 of such selector is energized over the following circuit: free pole of battery, 75 right winding of relay 14, conductor 15, upper armature and back contact of relay 16, conductor 17, finder brush 10, terminal 12, line conductor 18, sender S, the telephone set at substation A, conductor 19, terminal 80 13, brush 11, conductor 20, lower armature and back contact of relay 16, conductor 43, left winding of relay 14, to ground. The energization of relay 14 closes a circuit for relay 21 which is a slow acting relay. This 85 circuit is as follows: free pole of battery, relay 21, conductor 22, primary off-normal spring PON' closed to its upper contact only in the normal position of the selector, conductor 23, left armature and front contact of 90 stepping relay 14, conductor 24, outer armature and back contact of relay 25, to ground. The left-hand armature of slow relay 21 extends the back contact of the left armature of stepping relay 14 to the primary magnet 95 26. The attraction of the right-hand armature of relay 21 opens the circuit of conductor 28 to prevent the operation of the secondary stepping magnet 27.

The subscriber at substation A now op- 100 erates the sender S interrupting the line cir- circuit a number of times. Each time the sender S opens the line circuit the relay 14 is deenergized and at its left-hand armature and back contact closes the following cir- 105 cuit for primary magnet 26 to select the de- sired group of trunks: free pole of battery, conductor 29, primary stepping magnet 26, conductor 30, left armature and front contact 31 of slow relay 21, conductor 32, left 110

armature and back contact of line relay 14, conductor 24, outer armature and back contact of relay 25, to ground. Upon the first step of the selector shaft (not shown), the 5 spring PON' is transferred from engagement with its top contact and into engagement with its bottom contact. The momentary interruption of the circuit of relay 21 caused thereby is not sufficient to deenergize 10 the same. After the spring PON' engages its lower contact, the slow relay 21 is dependent for its continued energization upon the armature and back contact of the stepping relay 14, the impulses being received 15 over the following circuit: free pole of battery, slow relay 21, conductor 22, spring PON' and its bottom contact, conductor 33, left armature and front contact 34 of slow relay 21, conductor 32, left armature and 20 back contact of relay 14, conductor 24, outer armature and back contact of relay 25, to ground. Thus when the sender S at substation A reaches its normal position after having transmitted a series of interruptions 25 corresponding to the particular digit of the called number with which this selector is concerned, the slow relay 21 becomes deenergized due to the maintained energization of the stepping relay 14. Consequently, the 30 right-hand armature of this relay closes its back contact which completes a circuit for the secondary stepping magnet 27. This magnet makes and breaks its own circuit, thus stepping the selector brushes 35, 36, 37 35 over the group of trunks which has just been selected. This circuit is as follows: free pole of battery, conductor 38, secondary stepping magnet 27 and its armature and back contact, conductor 39, right armature and back contact of slow relay 21, conductor 28, contact spring PON², (which is closed 40 upon the first primary step of the selector shaft), conductors 41, 23, left armature and front contact of stepping relay 14, conductor 24, outer armature and back contact of relay 25, to ground. Idle trunks are those 45 upon whose test terminals 41 ground is present. Therefore, as soon as the test brush 37 engages a grounded test terminal 50 41, the following circuit is closed to stop the switch in engagement with the trunk represented thereby: free pole of battery, relay 16, conductor 42, relay 25, contact spring 44 controlled by said relay, its back 55 contact, conductors 45, 51, test brush 37 and test terminal 41 to ground. The relay 25 at its outer armature and back contact immediately opens the secondary stepping circuit just traced and, closing contact between 60 spring 44 and its inner armature, locks itself and relay 16 over the following circuit: free pole of battery, relay 16, conductor 42, relay 25, spring 44 and inner armature of said relay, conductor 46, armature and back contact of release magnet 47, to ground. The 65 relay 16 in transferring its armatures from their back to their front contacts, extends the calling line through to the next selector or connector, as the case may be, operating a relay thereat to remove ground from the 70 multiples 41 thereof to cause the same to test busy to other switches. The switch thus seized is then set under the control of the sender S at the calling substation A. The engagement of the outer armature of 75 relay 25 with its front contact prepares a circuit to release the selector when either of the subscribers to the connection hangs up his receiver, and grounds conductor 48 and test contact 41 in the well-known manner. 80 The placing of this ground upon such test conductor closes the following circuit to release the selector: free pole of battery, release magnet 47, conductor 49, primary off-normal spring PON³ now closed to its bottom contact, conductor 54, left armature and back contact of slow relay 21, conductor 32, left armature and back contact of relay 14, conductor 24, outer armature and front contact of relay 25, conductor 50, right armature and back contact of relay 14, conductor 51, test brush 37, to grounded test contact 41. The release magnet 47 locks 85 itself over the following circuit: free pole of battery, release magnet 47, conductor 49, primary off-normal spring PON³ and its bottom contact, conductor 52, armature and front contact of magnet 47, to ground. The energization of the release magnet 47 opens the locking circuit of relays 16, 25. The deenergization of the former again associates the relay 14 with conductors 17, 20. The closure of the outer armature of relay 25 to its back contact grounds conductor 53 leading back to the finder or equivalent switch 90 upon the closure of the primary off-normal spring PON³, when the selector completely restores. 95

What is claimed is:

1. In a machine switching telephone system, the combination with a selector, a stepping relay associated therewith, a sender for operating the same, a release circuit for said selector, a primary stepping circuit controlled by said relay, and a secondary stepping circuit, of a slow acting relay controlling said secondary stepping circuit and said release circuit at its armatures and back contacts, a circuit for said relay closed at the armature and front contact of said stepping relay, means for opening said circuit controlled by the selector shaft, and a circuit for maintaining said slow relay energized including an armature and back contact of said stepping relay. 100
2. In a telephone exchange system, the combination with a selector, trunks terminating therein, a stepping relay associated with said selector, a sender for operating the same, a primary stepping circuit con- 105

- trolled by said relay, a secondary stepping circuit, and a release circuit, of a slow relay adapted to be energized upon the energization of said stepping relay to open said release and secondary circuits, an off-normal contact spring for said selector adapted to transfer the control of said slow relay to the armature and back contact of said stepping relay upon the first primary step of said selector, said slow relay upon its deenergization upon the maintained attraction of the stepping relay armature being adapted to close the secondary stepping magnet circuit to cause the selector to hunt for an idle 5 trunk, said release circuit being controlled at a front contact of the stepping relay during the trunk hunting operation.
3. In a machine switching telephone system, the combination with a selector, a stepping relay associated therewith, a sender for operating the same, a release circuit for said selector, a primary stepping circuit controlled by said relay, and a secondary stepping circuit, of a slow acting relay adapted when energized to interpose a break in the secondary stepping circuit and in the release circuit, and to prepare the primary stepping circuit, a circuit for said relay closed at the armature and front contact of said stepping relay, means for opening said circuit controlled by the selector shaft, and a circuit for maintaining said slow relay energized including an armature and front contact thereof, and an armature and back contact of said stepping relay.
4. In a machine switching telephone sys-
- tem, the combination with a selector, a stepping relay associated therewith, a sender for operating the same, a release magnet for said selector, a circuit therefor, a primary stepping circuit controlled by said relay, and a secondary stepping circuit, of a slow acting relay controlling said secondary stepping circuit and said release circuit at its armature and back contact, a circuit for said slow relay closed at the armature and front contact of said stepping relay, means for opening said circuit controlled by the selector shaft, a circuit for maintaining said slow relay energized including an armature and back contact of said stepping relay, means for closing said release circuit, a locking circuit for said release magnet, and an off-normal contact controlling said locking circuit.
5. In a machine switching telephone system, the combination with a selector, a stepping relay associated therewith, a sender for operating the same, a release circuit for said selector, a primary stepping circuit controlled by said relay, and a secondary stepping circuit, of a slow acting relay controlling said secondary stepping circuit and said release circuit at its armatures and back contacts, a circuit for said relay closed at the armature and front contact of said stepping relay, and a contact controlled by the selector shaft for transferring the control of said slow relay to the back contact of said stepping relay.

In witness whereof I hereunto subscribe my name this 3rd day of June A. D. 1915.

BERT G. DUNHAM.
